AUTOMATIC VOLUME CONTROL

James R. Nelson, Cambridge, Mass., assignor to
Raytheon Production Corporation, Newton,
Mass., a corporation of Delaware

Application May 27, 1931, Serial No. 540,276

6 Claims. (Cl. 250—20)

This invention relates to an automatic volume control for a receiver of modulated radio frequency waves. Among the objects of my invention is the provision of a device which will keep the output of such a receiver at a constant level. Another object is to provide means whereby the regulation of said device is not exerted when a signal of low value is received, but only comes into operation when the signal exceeds a certain predetermined value.

The foregoing and other objects of my invention will be best understood from the following description of exemplifications thereof, reference being had to the accompanying drawing, wherein

15 Fig. 1 is a diagram of the circuits involved in a receiving set incorporating my present invention; and

Fig. 2 is a diagram of the circuits involved in a similar set, showing a slightly different modified embodiment of my invention.

20 One of the difficulties met with in modern radio broadcast receiving is that the signal strength of a station as received by a broadcast receiving set often fluctuates quite widely. With the ordinary broadcast receiver, the set is adjusted so that at 25 a certain value of signal strength, the output volume is of the desired value. However, when the magnitude of the received signal changes, the output volume also changes, and is either too 30 loud or too soft. In accordance with my invention I eliminate this difficulty by providing an amplifier with means whereby above a certain value of signal strength, the amplifying power thereof is varied inversely with the signal strength, and thus the output level is maintained at a constant value.

In order to understand the operation of my arrangement, it is necessary to consider certain theoretical aspects of the operation of a space discharge device. In a space discharge device or tube, including a cathode, anode and control electrode, the theoretical voltage amplifying power of the tube, which is ordinarily represented as μ is usually determined by the geometry of the tube. With the ordinary three-element tube μ is practically constant. With other types of tubes, such as, for example, the screen-grid type of tube, μ varies somewhat with different voltages applied to the control grid and plate. The mutual conductance of a tube, which is represented by g_m , represents the real function of the device when used as an amplifier. The value of g_m is obtained from the following equation:

$$g_m = \frac{\mu}{r_n} \quad \text{(Equation 1)}$$

where r_p is the anode or plate circuit resistance. By multiplying the signal voltage e_g as applied to the grid by the mutual conduct-

ance g_m , we find the amount of alternating current i_p set up in the plate circuit by the signal.

$$e_g g_m = i_p \quad \text{(Equation 2)}$$

This is based on the assumption that there is no external impedance in the plate circuit. Any such impedance will decrease the theoretical value of i_p obtained as above.

In accordance with my invention, I obtain a constant signal output from an amplifier by causing the plate circuit resistance to vary in a pre-determined manner in accordance with the variation in signal strength impressed on said amplifier. In tubes in which μ also varies, I cause the variation of r_p to be substantially in excess of any corresponding variation in μ . This variation in plate circuit resistance causes a corresponding variation in g_m of the tube. I arrange my device so that g_m , the mutual conductance of the tube, varies above a certain signal strength substantially inversely as the signal strength impressed on said tube.

When a negative bias is impressed upon the grid of a tube, there is introduced into the tube a resistance to the electron flow between the cathode and the plates. This manifests itself in an increase in the plate circuit resistance. As the negative bias on the grid increases in value, the resistance of the plate-circuit likewise increases. I obtain my variation in plate circuit resistance or g_m , as called for above, by impressing a negative bias on the grid of an amplifying tube, and varying said negative bias in accordance with the signal strength received by my device. As stated above, the value of μ in three-element tubes is not substantially affected by changes in grid bias while in tubes of the screen-grid type, μ increases with increases in negative bias on the control grid. However, r_p of such screen grid tubes increases much faster than does μ with increases of control grid negative bias. Thus in each case the desired variation in g_m is obtained with variations in said bias.

and a control grid 10. The control grid is connected to the non-grounded side of the coil 5 and condenser 6. A coil 11 is included in the output circuit of the plate 9, whereby the output of stage 1 is inductively coupled to the detector stage 2 by means of a coil 12. A radio frequency bypass condenser 44 may be connected between the cathode 8 and one end of the coil 11, as shown.

10 In the detector stage 2, the coil 12 has connected across it the usual variable condenser 17. The detector stage also includes a tube 13. This tube comprises a cathode 14, a plate 15, and a control grid 16. The control grid 16 is connected to one side of the coil 12 and condenser 17, through the grid-condenser 18. A high leak resistance 18' is connected across the condenser 18. A resistance 21 is connected in series with the plate 15 in the output circuit of said plate. An audio frequency bypass condenser 45 is connected between the cathode and end of the resistance 21 opposite the plate 15 in order to provide a return path for the audio frequency currents. A radio frequency bypass condenser 46 may be provided to provide a bypass for any radio frequency currents which tend to pass through the output circuit of the plate 15. In the cathode return connection of the plate 15 is placed a resistance 22 which is shunted by a condenser 23 and a high resistance 23' in series. The end of coil 5 connected to the condenser 41 is also connected through a resistance 40 to the point between the condenser 23 and the resistance 23'.

35 The cathode 14 and the sides of coil 12 and condenser 17 opposite the grid 15 are also connected to the conductor 19 which is grounded at 20. This conductor may be, for example, the grounded frame of a radio set.

40 Audio stage 3 includes a tube 24, comprising a cathode 25, a plate 26, and a control grid 27. The variations in potential on the plate 15 of the detector stage 2 are impressed on the grid 27 of the audio stage 3 by means of a condenser 28. An output device 29, which may be, for example, 45 a loud speaker, is connected in the output circuit of the plate 26. In the cathode return connection of the plate 26 is placed resistance 30 bridged by a condenser 31. The condenser 31 is large enough so as not to offer any considerable 50 impedance to audio frequency currents. The power which can be dissipated in the plate 26 is a limited value, and the power so dissipated is a maximum under no signal conditions. By inserting the resistance 30, the current through the plate 26 is kept at a safe value under no signal 55 conditions, even with the use of a fairly high voltage on the plate. This arrangement permits the use of a higher voltage on the plate 26 than could otherwise be used, and results in an increase in the power obtainable from the tube 24. The condenser 28 is connected through a resistance 42 to the end of resistance 30 opposite the cathode 25. The grid is connected by a variable tap 43 to any desired point on resistance 42.

60 The circuits are supplied with the proper direct current potentials from a voltage divider, which consists of a resistance 32 connected across the source of direct current, which may be, for example, a battery 33.

70 The plate 26 is connected through the output device 29 to one terminal 34 of the resistance 32. The cathode 25 is connected through the resistance 30 to the other terminal 35 of said resistance 75 32.

The plate 15 is provided with the proper potential from a tap 36 on the resistance 32. This potential is preferably somewhat lower than that applied to the plate 36. An audio frequency choke 47 may be placed in the connection to plate 15, as shown, whereby the audio frequency currents are prevented from flowing through the resistance 32. Instead they return to the cathode through the condenser 45. The cathode 14 of the tube 13 is connected as is the cathode 25 to the terminal 35.

The plate 9 of the tube 7 is also provided with a suitable potential from a tap 37 on the resistance 32. This potential is preferably lower than that applied to either plates 15 or 26. The 15 cathode 8, however, instead of being connected directly to the terminal 35 is connected to a tap 38 spaced from said terminal 35 on the resistance 32.

20 Although I have described above and have illustrated diagrammatically in the drawing three-element tubes in each of the stages, I wish it to be understood that various types of tubes may be used in these stages. In stage 1, for example, tube 7 may consist of a triode of the 227 type, or it may consist of a screen-grid tetrode of the 224 type. If a screen-grid tube is used, the screen grid itself is maintained at a definite potential with respect to the cathode in accordance with the usual practice. In stage 2, a three-element 30 tube of the 227 type could be used, although I prefer to use a screen-grid detector tube of the 224 type. The connections of the screen grid in this type would likewise be made in the conventional manner. In stage 3 a power amplifier tube of the 245 type could be employed. However, a pentode tube of the 247 type could be utilized in this stage. Although I have mentioned specific tubes above, I wish it to be understood that any type of tube which has the necessary characteristics could be employed in any of the stages.

35 The operation of the device, as described above, can be best understood from a consideration of the theory of operation of a tube connected as is the device 13 in Fig. 1. In such a tube the condenser 18 and resistance 18' serve to impress a negative potential upon the grid 16, which potential varies in accordance with the average value of the magnitude of the radio frequency 50 signal impressed on said grid. Thus, as the magnitude of the signal increases, the negative bias on the grid 16 will increase. As is well known, an increase in negative bias on the grid will cause a decrease in the current flowing to the plates. The constants of the condenser 18 and resistance 18' are so chosen that when a modulated signal is received, the variations in voltage on the grid 16 closely follow the modulation frequency carried by the radio frequency 60 signal wave.

45 In addition to the audio frequency variation, the signal is sometimes subject to a slower variation in signal strength. If we compare an unmodulated radio frequency wave and a wave of the same intensity carrying an audio frequency modulation, we find that the average magnitude of each of said waves over a period of time which is considerably greater than the period of the audio frequency, do not differ from each other to any considerable degree. Changes in this average value occur only with changes in signal strength. The changes in signal strength with which we are concerned usually occur at a rate which is considerably slower than that of any 75

audio frequency which may be received. Therefore we see that the negative bias on the grid 16 will not only follow the audio frequency modulation, but will also vary in magnitude in accordance with the slower variations in signal strength. The device, as shown in Fig. 1, utilizes this slower variation in grid bias to compensate for the variation in the strength of the signal received in the set. This occurs in the following manner.

Let the values of certain currents and resistances in Fig. 1 be indicated by the following symbols:

15 V_{10} =grid bias in grid 10
 R_1 =resistance between 35 and 38
 R_2 =resistance of 22
 i_9 =current in circuit of plate 9
 i_{15} =current in circuit of plate 15
 i_{16} =current through R_2
 i_{10} =current through R_1
 i_{11} =current through 32 between po

In each case i is the average of the current flowing through its respective circuit, said average being taken over a period of time considerably in excess of the audio frequency period. Such an average current can be considered as the direct current component of the current flowing in its respective circuit.

With no signal received by the set, the voltage between the grid 10 and the cathode 8 of the space discharge device 7 is

$$V_{10} = -(i_{10}R_1 - i_{16}R_2) \quad \text{(Equation 3)}$$

35 The values of the resistance R_1 and R_2 and the other constants of the circuits are so chosen that with no signal received by the set, $i_{10}R_1$ is greater an absolute value than $i_{10}R_2$ to such an extent that proper negative bias is impressed upon the grid. 39

When receiving a signal, condensers 6 and 17 are adjusted so that their respective circuits are tuned to the desired signal frequency being received in the antenna circuit 4. This signal is amplified in stage 1 and the voltage variations produced thereby are impressed on the grid 16 of the space discharge device 13 by means of the coil 12. Due to the action of the grid condenser and the resistance 18 connected across it, the grid bias on the grid 16 will vary in accordance with the audio frequency modulation of the signal and also in accordance with the slower changes in signal strength as described above. The tube acts so as to produce a corresponding variation in current in the plate 15 in an amplified degree. As has been indicated above, the variations in current in the plate circuit take place in such a manner that the current decreases upon an increased negative bias on the grid. Thus an increase in signal strength will result in a decrease in the direct current component i_{15} of the plate current. Since the value of current flowing through R_2 , due to the grid 10, is negligible with respect to that, due to i_{15} , for all practical purposes it can be said that i_{15} is equal to i_8 .

By referring to Equation 3, it will be seen that a decrease in the value of i_{16} will result in an increase of the negative bias V_{10} on the grid 10. This increase in negative bias produces an increase in plate resistance r_p and a corresponding decrease in g_m of the tube 7, in accordance with the explanation above.

Thus it will be seen that when the signal voltage e_g applied to the tube 7 increases, the value of g_m of that device decreases. Since from Equa-

tion 2, i_p is the product of g_m and e_g , the fact that they vary in opposite directions produces a tendency for the amount of alternating current i_p set up in the circuit of plate 9 to remain constant. Therefore, the strength of the signal output in the amplifier stage 1 as impressed on the detector 2 tends to remain practically constant. Accordingly the output of detector 2 and consequently of the set likewise tends to remain at a constant level.

Since the audio frequency is subjected to considerable variations in amplitude and since it is desired to reproduce these variations, it is desirable to prevent the audio frequency current from passing through the resistance R_2 and varying the bias on the grid 10. In Fig. 1 I accomplish this result first by providing a condenser 45 which allows the audio frequency to return from the plate to the cathode without going through the circuit which includes the resistance R_2 . If desired a choke 47 may also be provided which prevents the audio frequency currents from passing to the cathode through the circuit including the resistance R_2 . Thus only the direct current component i_{15} of the plate current is allowed to flow through R_2 .

Although I have provided the arrangement as recited above for keeping audio frequency currents out of the circuit involving R_2 , yet it is possible that small audio frequency currents may appear in this circuit. This is particularly true if the source of potential 33 is the output of a rectifier which is not perfectly filtered. The voltage of such currents will be taken up in a major degree by the drop in the choke 47 and in the resistance 32. Thus a very small audio frequency voltage may appear across the terminals of R_2 . Since it is clear that this audio frequency potential bears no relation to the strength of the signal to be compensated for, it is desirable to eliminate the effect of this drop across the resistance R_2 . The arrangement of the condenser 23 and the resistance 23' effectively eliminates even this slight effect. The condenser 23 is of fairly large value so that it offers very little impedance to audio frequency currents. The resistance 23', however, is of a large value so that its impedance is great as compared to that of the condenser 23. The circuit comprising the condenser 23 and the resistance 23' and the circuit comprising the resistance R_2 afford two parallel paths for the passage of audio frequency currents in the circuit in which they are placed. The audio frequency drop across R_2 will of course be equal to the total audio frequency drop across 23' and the condenser 53

23. Since, however, the impedance of the resistance 23' is large with respect to that of the condenser 23, practically the entire drop across these two elements will appear across the resistance 23'. Thus the magnitude of the audio frequency drop across the resistance 23' is substantially equal to the audio frequency drop across the resistance R_2 . It will be seen that the resistance 23' is connected in such a manner in the circuit of the grid 10 that its audio frequency drop is directly subtracted from the audio frequency drop appearing across the resistance R_2 . Thus any audio frequency voltage appearing across R_2 is directly compensated for by a similar audio frequency voltage appearing across the resistance 23'. The condenser 41 is necessary to prevent the effect of the resistance 23' from being short-circuited by the ground connection 19. The resistance 40 is provided in order that the total resistance of the path across the condenser 41 is 75

high enough to prevent the passage of an appreciable amount of radio frequency current. The radio frequency currents are provided with a return path from the plate to the cathode by means of the condenser 44. Of course the frequency of the variation in the direct current component of the plate current, due to the variation in signal strength which we are attempting to compensate, is so slow that its effect on the condenser 23 is practically that of a direct current. Therefore the presence of the circuit comprising the resistance 23' and condenser 23 across the resistance R_2 does not affect the regulating property of the resistance R_2 on the bias of the grid 10.

In addition to eliminating the effects of the audio frequency drop across the resistance R_2 , it is desirable that the length of time which it takes for the regulator to respond to changes in signal strength impressed on the grid 16 shall be made comparatively large. For example, when tuning the set to the desired signal, the tuning elements should be adjusted so that the set will respond in maximum degree to the desired signal. Under these conditions the value of the signal will usually be well above the point at which an appreciable volume regulation is obtained. Thus a considerable variation in signal strength in either direction can occur without affecting the volume output of the set. If the volume control were to respond too quickly as the operator varied his condensers for purposes of tuning, the volume output of the set would remain constant over a fairly wide band. This would be due to the fact that as the tuning approached the resonance condition of the set, a certain predetermined value of signal strength would be reached at which the volume control would start to operate. As the tuning more nearly approached the resonant point, the signal strength would increase, but the response of the volume control would be rapid enough to follow the rate at which said point was approached. This action would continue as the tuning passed the resonant frequency point until the signal decreased on the opposite side of said point to the predetermined value at which the volume control no longer exerted an appreciable effect. Thus it would be very difficult for the operator to determine the resonant point for a particular frequency. However, if the rate at which the volume control responds were made slow enough, the operator could tune the set to its maximum volume output and the response of the volume control would not be rapid enough to follow the rate at which the adjustment of the tuning elements took place. I make the response of my volume control very slow by making the time constant of the circuit, comprising the resistances 22, 23' and the condenser 23, large. Since the time constant of such circuit depends upon the value of resistance therein, I make this constant large by making the value of the resistance in the circuit large. Since resistance 22 is placed directly in the plate circuit of the device 13, any drop across this resistance decreases the plate voltage of said device. Therefore, this resistance R_2 is limited in actual practice to comparatively low values. However, the value of resistance 23' in no way affects the plate voltage of the device 13. Therefore, this resistance may be made as large as is desirable. I therefore select a value of R_2 which will not affect the plate voltage to an undesirable extent, and make the value of the resistance 23' large enough so that the time constant of its

circuit is quite large. This time constant may be, for example, about one-twentieth of a second. Also as pointed out above, the larger the value of resistance 23', the smaller need be the value of the capacity of condenser 23. With the circuit arranged as above, any variations in output of detector 2 which occur at a rate greater than that determined by the time constant of the regulator circuit will not affect to an appreciable degree the value of the current i_{16} flowing through R_2 . Therefore, this device will respond only to very slow changes in signal strength which is the result desired. Of course it is clear that the value of the time constant of the regulating circuit can be adjusted by adjusting the value of the resistance 23'. 5 10 15

The value of the signal received by a set is often of such a low value that it is desired to amplify this signal to the full extent of the set. Furthermore, an increase in magnitude of such a weak signal will not produce an excessive output in the set. Therefore it is desirable to arrange the device as described above so that it will not exert regulation upon signals below a certain value. This is exactly what I accomplish by another feature of my present invention which is incorporated in the arrangement as shown in Fig. 1. In the analysis as given above, the entire variation in the voltage V_{10} on the grid 10 was attributed to the change in i_{16} . 20 25 30 This is substantially true if the signal received by the set is above a certain value. At signal values, however, below this value, the bias on grid 10, due to the drop in R_1 and R_2 , is comparatively small. As is evident from the analysis 35 in the early part of the specification, the value of the direct current component i_9 of the current of plate 9 flowing in the circuit of plate 9 under these conditions is comparatively large. Due to the fact that the radio frequency currents are bypassed by the condenser 44, practically the only portion of the current of plate 9 that will flow through the circuit, including the resistance R_1 , will be the direct current component i_9 . The current i_{10} through R_1 consists 40 45 of the sum of the currents i_9 and i_{11} . i_{11} is practically constant and depends primarily upon the resistance 32 and the value of the voltage source 33. I select the values of the constants of my device so that at signals below a certain intensity, current i_9 forms a substantial part of the current i_{10} . Upon the strength of the signal increasing, the grid 10 becomes more negative, as shown above, and the current i_9 decreases. At 50 55 low values of signal strength, this decrease in the current i_9 will produce an appreciable decrease in the value of i_{10} . From Equation 3 it will be noted that decrease in i_{10} will tend to produce a decrease in the negative bias V_{10} as applied to the grid 10. At the same time, however, the increase in signal strength will cause i_{16} to decrease. The decrease in i_{16} will tend to cause an increase in V_{10} . Thus it will be noted that the variations in i_{16} and i_{10} operate on the bias of grid 10 in opposite directions. The constants of the circuits may be so chosen that at 60 65 a predetermined value of signal strength, the effects of these two currents practically balance one another so that very little effect is had upon the signal received. This signal is therefore allowed to be amplified almost to the full capacity of the set. However, as the strength of the signal increases, the magnitude of V_{10} and consequently the magnitude of i_9 becomes smaller. Since i_{11} remains practically constant, i_9 at 70 75

certain higher values of signal strength no longer forms a substantial part of the current i_{10} . Therefore, the variations in the value of i_9 under these conditions will not produce appreciable variations in the value of i_{10} . At such higher values of signal strength, practically the entire regulating effect is obtained through the variations of i_{15} . Thus the regulation will not become effective to an appreciable degree until a predetermined value of signal received is reached.

The arrangement as described above will tend to produce a constant level of output from the set. Since it is often desirable to adjust this level to suit varying conditions and varying tests, I have provided means whereby a particular level may be selected, which level will automatically be maintained by my device. This is accomplished by means of the tap 43 on the resistance 42 in the audio stage 3. By varying the position of the tap 43 on the resistance 42, any desired proportion of the total voltage variations appearing on the plate 15 and consequently the condenser 28 may be selected. If the tap 43 is placed at the upper end of the resistance 42, the total output of the detector stage 2 will be amplified and the maximum output will be obtained in the set. However, as the tap 43 is moved down along the resistance 42, only a portion of the output voltage of the detector stage 2 is impressed on the grid 27 of the audio stage 3. Thus the level of the output of the set is decreased. It will be noted, however, that the regulating effect of my automatic volume control is not distributed by this latter arrangement. Any volume level which is selected by adjusting the tap 43 will automatically be maintained by my regulating arrangement.

In Fig. 2 I have illustrated a slightly modified form of my invention. In this figure I have applied the same reference numerals to those elements which are identically the same as those shown in Fig. 1. I have illustrated an additional radio frequency amplification stage 50 which is exactly the same as stage 1. This is interposed between the antenna circuit 4 and the stage 1, and is coupled to said circuits by means of coils 51 and 52, respectively. Stage 50 includes a tube 53 including a cathode, anode and control electrode. The cathodes of tubes 53 and 7 are connected together by means of the conductor 54 while the ends of the inductance elements 51 and 52 opposite the grids of their respective tubes are connected together by means of a conductor 55. It will be noted that in Fig. 2 the effect of the two radio frequency amplification stages acts on the remainder of the circuit exactly the same as does the single radio frequency stage illustrated in Fig. 1. The current i_9 is the sum of the direct current components of the plates of both tubes 53 and 7 while the varying bias of the regulating device is impressed upon the grids of both of said tubes.

The magnitude of signal voltage at which the regulating device becomes effective is fixed in the arrangement, as shown in Fig. 1, by the values of the resistances as originally chosen. It is often desirable to regulate the value of signal voltage at which the regulation becomes appreciable. I accomplish this result by means of a simple expedient as illustrated in Fig. 2. The point intermediate the resistances 22 and 23' is connected through an additional resistance 56 to the point 38 on the resistance 32. The cathodes of tubes 53 and 7 instead of being connected directly to the point 38 are connected by

means of a variable tap 57 to any desired point on said resistance 56. In Fig. 2 I have shown the tap 57 as being set in a predetermined position. The amount of resistance 56 between the tap 57 and the point 38 is indicated as R_3 , and the value of said resistance between the tap 57 and the point intermediate the resistances 22 and 23' is indicated as R_4 . It will be noted that current i_9 divides at tap 57, a certain amount i_{12} flowing through resistance R_{13} , and the remaining portion of i_9 which is indicated as i_{13} flowing through R_4 . Current i_{16} which flows through R_2 now consists of the sum of i_{15} and i_{13} . Any decrease in the total current i_{16} increases the negative bias on the grids of the radio frequency amplifiers as explained in relation to Fig. 1. Current i_{10} now consists of the sum of i_{11} and i_{12} . Any decrease in i_{10} causes a decrease in the negative bias on the grids of the radio frequency amplifiers. By dividing the current i_9 in the manner indicated, it is clear that variations in i_{12} and variations in i_{13} act on the grid bias of the radio frequency amplifiers in opposite directions. By adjusting the position of tap 57, the relative proportion of i_9 which flows through R_3 and R_4 may be regulated. Since the ineffectiveness of the regulator at low values of signal voltage depends largely on the proportion of the current i_9 which flows through the resistance R_1 , it will be seen that by adjusting the proportion of i_9 which flows through said resistances, the value of signal voltage at which the regulating effect of the device becomes appreciable is likewise controlled.

The invention is not limited to the particular details of construction as described above, as many equivalents will suggest themselves to those skilled in the art. For example, any type of space discharge device, among which may be tubes of the screen-grid type, may be used instead of the three-element tubes as shown in the drawing. Also various different types of circuits may be used in the set instead of the particular one as illustrated. It is accordingly desired that the appended claims be given a broad interpretation commensurate with the scope of the invention within the art.

What is claimed is:

1. A carrier wave device, including a radio-frequency amplifier having a tube containing a cathode, an anode, and a control grid, a detector, means for causing the output of said detector to decrease with an increase in the modulation component and in the strength of the carrier wave, a source of potential for said receiver, a voltage-dividing impedance across said source, said amplifier and detector being connected to said voltage-dividing impedance so that the output of said amplifier and detector flow through portions of said voltage-dividing impedance, an additional impedance in the output of said detector, said additional impedance being connected to said voltage-dividing impedance to obtain a regulating voltage which is the difference between the drop across a portion of said voltage-dividing impedance and said additional impedance, and means associated with said last-named impedances and said control grid to impress on said control grid a negative bias which increases with an increase in the strength of the carrier wave only above a certain predetermined strength.

2. A carrier wave device, including a radio-frequency amplifier, a detector, means for causing the output of said detector to vary with variations in the modulation component and in the strength

of the carrier wave, a source of potential for said receiver, a voltage-dividing impedance across said source, said amplifier being connected to said voltage-dividing impedance so that its output flows through a portion of said voltage-dividing impedance, an additional impedance in the output of said detector, said additional impedance being connected to said voltage-dividing impedance to obtain a regulating voltage which is the difference between the voltage drop across a portion of said voltage-dividing impedance and said additional impedance, and means associated with said last-named impedances and said amplifier to impress upon said amplifier a volume control voltage which varies in accordance with the strength of the carrier wave only above a certain predetermined strength.

3. An automatic volume control device including a radio-frequency amplifier having a tube in which the discharge is controlled by a control grid, a detector, means for causing the output of said detector to vary with the strength of the carrier wave, an impedance, connections from the output circuits of said amplifier and detector to portions of said impedance for causing the output of said amplifier and detector to flow through said portions of said impedance, an additional impedance in the output circuit of said detector, said additional impedance being connected to said first-named impedance to obtain a regulating voltage which is the difference between the drop across a portion of said first-named impedance and said additional impedance, and means associated with said last-named impedances and said control grid to impress on said control grid a negative bias which increases with an increase in the strength of the carrier wave only above a certain predetermined strength.

4. An automatic volume control device including a radio-frequency amplifier having a tube in which the discharge is controlled by a control grid, a detector, means for causing the output of said detector to vary with the strength of the carrier wave, an impedance, connections from the output circuits of said amplifier and detector to different portions of said impedance for causing at least portions of the output of said amplifier and detector to flow through said different portions of said impedance, an additional impedance in the output circuit of said detector, said additional impedance being connected to said first-named im-

pedance to obtain a regulating voltage which is the difference between the drop across a portion of said first-named impedance and said additional impedance, and means associated with said last-named impedances and said control grid to impress on said control grid a negative bias which increases with an increase in the strength of the carrier wave only above a certain predetermined strength.

5. An automatic volume control device including a radio-frequency amplifier having a tube in which the discharge is controlled by a control grid, a detector, means for causing the output of said detector to vary with the strength of the carrier wave, a source of potential for said receiver, a voltage-dividing impedance across said source, said amplifier and detector being connected to said voltage-dividing impedance so that the output of said amplifier and detector flow through portions of said voltage-dividing impedance, an additional impedance in the output of said detector, said additional impedance being connected to said voltage-dividing impedance to obtain a regulating voltage which is the difference between the drop across a portion of said voltage-dividing impedance and said additional impedance, and means associated with said last-named impedances and said control grid to impress on said control grid a negative bias which increases with an increase in the strength of the carrier wave only above a certain predetermined strength.

6. An automatic volume control device including a radio-frequency amplifier, a detector, means for causing the output of said detector to vary with variations in the strength of the carrier wave, a source of potential, an impedance across said source, said amplifier being connected to said impedance so that its output flows through a portion of said impedance, an additional impedance in the output of said detector, said additional impedance being connected to said first-named impedance to obtain a regulating voltage which is the difference between the voltage drop across a portion of said first-named impedance and said additional impedance, and means associated with said last-named impedances and said amplifier to impress upon said amplifier a volume control voltage which varies in accordance with the strength of the carrier wave only above a certain predetermined strength.
